(57) **CLAIM**

The ornamental design for a bar code scanner handle, as shown and described.

DESCRIPTION

FIG. 1 is perspective view of the top, front, and left side of a bar code scanner handle showing my new design;

FIG. 2 is a left side view thereof, the right side view being a mirror image;

FIG. 3 is a front view thereof;

FIG. 4 is a back view thereof;

FIG. 5 is a top view thereof; and,

FIG. 6 is a bottom view thereof.

The broken lines shown in FIGS. 1-6 are for illustrative purposes only and form no part of the claimed design.
